UNITED STATES PATENT OFFICE

JOHN C. STOKES, OF HOUSTON, TEXAS, ASSIGNOR TO REED ROLLER BIT COMPANY, OF HOUSTON, TEXAS, A CORPORATION OF TEXAS

OVERSHOT

Application filed June 11, 1929. Serial No. 369,991.

This invention relates to deep well drilling apparatus and more particularly to overshots of that general type disclosed by my Letters Patent of the United States No. 1,442,188, of 5 January 16th, 1923.

The overshot provided by the present invention is particularly adapted to remove from a drill stem collapsible bit carriers or core barrels, but may also be used to remove 10 other devices provided with means adapted to be engaged thereby.

The conventional collapsible bit carrier is provided with a conical head, and the conventional overshot with a pair of pivoted 15 dogs. The carrier is usually dropped into the drill stem and descends to the lower end thereof to support the collapsible blades in their expanded positions. When it is desired to remove the carrier to mount new blades 20 therein, the overshot is lowered into the drill stem by means of a suitable cable until the pivoted dogs engage the conical head, after which the overshot and carrier connected thereto may be removed from the drill stem.

25 At times the carrier or other device becomes jammed or stuck in the bit head, and when the overshot is made to engage the same and an excessive pull is exerted on the cable, the cable breaks, and the removal of the carrier 30 and overshot thereby left in the stem is a difficult and expensive task.

This invention has for one of its objects 35 the provision of a new and improved overshot adapted to positively grip the conical head of a carrier or the like, but to release it when more than a predetermined resistance is offered to its removal.

40 Other objects of the invention will herein-after appear.

45 In the accompanying drawings which are illustrative of the preferred embodiment of the invention, Fig. 1 is a sectional elevation of the overshot engaging the conical head of a bit carrier; Fig. 2, a fragmentary view similar to Fig. 1 illustrating the relative positions of the overshot and the carrier immediately before they are locked together; Fig. 3, a fragmentary side elevation of the overshot; and Fig. 4, a horizontal section on the line 50 4—4 of Fig. 3.

The overshot is indicated generally at O and the carrier at C. The overshot comprises a substantially cylindrical bifurcated body the upper end of which is provided with a screw threaded shank 1 whereby it may be 55 attached to a suitable element to which the cable is attached. The spring fingers 2 and 3 of the overshot are provided, respectively, with internal arcuate flanges 2^a and 3^a. The upper sides 2^a' and 3^a' of these flanges are 60 slightly inclined downwardly and inwardly; and the lower sides 2^a'' and 3^a'' of which are greatly inclined upwardly and inwardly.

65 The grip of the spring fingers 2 and 3 may be varied by the bolt 4.

The carrier C is provided with a head having a conical section 5, a cylindrical section 6 and a frusto-conical section 7.

Assuming that the carrier 6 is in position 70 in the lowermost end of the drill stem, and its removal is desired, the overshot O is attached to the end of a cable and lowered in the drill stem. The spring fingers 2 and 3 are forced apart by the entrance of the head of the carrier therebetween. The lower sides 75 2^a'' and 3^a'' of the flanges 2^a and 3^a move over the conical section 5 of the carrier so that the flanges 2^a and 3^a may pass over the cylindrical section 6, whereupon the fingers 2 and 3 are permitted to move toward each other and the 80 upper sides 2^a' and 3^a' of the flanges are carried into contact with the frusto-conical section 7.

Under normal conditions, the overshot may 85 be elevated by the cable and will bring the carrier with it. But if the carrier C is jammed or stuck in the drill stem and more than a predetermined pull is necessary to release it, when said pull is applied to the overshot, the upper sides 2^a' and 3^a' of the flanges 90 2^a and 3^a will move outwardly over the frusto-conical section 7 thereby forcing the fingers apart so that the flanges 2^a and 3^a may move over the cylindrical section 6; and the overshot will be thereby released from the carrier. Danger of breaking the usual cable is 95 thus eliminated.

The overshot may then be removed from the stem and a stronger cable connected thereto. The bolt 4 may then be tightened to offer more 100

resistance to the separation of the fingers 2 and 3. The overshot may then be again lowered into the stem and made to engage the head of the carrier in the manner described above. When an upward pull is exerted on the overshot, the resistance offered by the bolt 5 to the separation of the fingers 2 and 3, is sufficient to prevent outward movement of the sides 2^a and 3^a on the frusto-conical section 7, and so the carrier may be forcibly removed.

10 Or, if for any reason it is advisable to force the carrier out of the drill stem, the drill stem itself with the carrier therein may be removed from the hole after the release of 15 the carrier by the overshot has indicated that the carrier is stuck in the stem.

Various uses of the overshot other than that herein described will occur to those skilled in the art, and no limitation in this 20 respect is to be inferred; and various changes may be made in the preferred embodiment illustrated within the scope of the following claims.

I claim:

25 1. An overshot having a pair of spring fingers constructed to yieldably resist separation, said fingers having internal flanges, the upper sides of said flanges being inclined downwardly and inwardly.

30 2. An overshot having a pair of spring fingers constructed to yieldably resist separation, said fingers having internal flanges, the upper sides of said flanges being inclined downwardly and inwardly, and the lower 35 sides of said flanges being inclined upwardly and inwardly.

3. An overshot having a pair of spring fingers constructed to yieldably resist separation, said fingers having internal arcuate flanges, the upper sides of said flanges being 40 inclined downwardly and inwardly.

4. An overshot having a pair of spring fingers constructed to yieldably resist separation, said fingers having internal arcuate flanges, the upper sides of said flanges being 45 inclined downwardly and inwardly, and the lower sides of said flanges being inclined upwardly and inwardly.

5. An overshot having a pair of spring 50 fingers constructed to yieldably resist separation and an adjustable bolt to vary the grip of said fingers.

6. An overshot having a pair of spring fingers constructed to yieldably resist separation, said fingers having internal flanges, the upper sides of said flanges being inclined downwardly and inwardly, and an adjustable bolt to vary the grip of said fingers.

7. An overshot having a pair of spring 60 fingers constructed to yieldably resist separation, said fingers having internal arcuate flanges, the upper sides of said flanges being inclined downwardly and inwardly, and an adjustable bolt to vary the grip of said 65 fingers.

8. The combination with a device having a head, the lower surface of said head being inclined upwardly and outwardly, of an overshot having a pair of spring fingers, said fingers having flanges to engage said head. 70

9. The combination with a device having a head, the lower surface of said head being inclined upwardly and outwardly, of an overshot having a pair of spring fingers, said fingers having flanges to engage said head, 75 the upper sides of said flanges being inclined downwardly and inwardly.

10. The combination with a device having a head, the lower surface of said head being inclined upwardly and outwardly, of an overshot having a pair of spring fingers, said fingers having flanges to engage said head, 80 the upper sides of said flanges being inclined downwardly and inwardly, and an adjustable bolt to vary the grip of said fingers. 85

11. An overshot having a pair of spring fingers constructed to yieldably resist movement from their active positions, said fingers having gripping members, the upper sides of 90 said members being inclined downwardly and inwardly.

12. An overshot having a pair of spring fingers constructed to yieldably resist movement from their active positions, said fingers having gripping members, the upper sides of 95 said members being inclined downwardly and inwardly, and an adjustable bolt to vary the said resistance of said fingers.

13. A device of the character described having a head, said head having a lower surface inclined upwardly and outwardly. 100

14. A device of the character described having a head, said head having a conical section and an inverted frusto-conical section.

15. A device of the character described having a head, said head having a conical section, an inverted frusto-conical section, and an intermediate cylindrical section, the diameters of said cylindrical section, the base of said conical section, and the base of said 105 frusto-conical section being substantially equal. 110

In testimony whereof, I hereunto affix my signature.
